GAS ELIMINATOR AND FUEL ECONOMIZER

Addison C. Hoof, Hinsdale, Ill.

Application January 22, 1938, Serial No. 186,446

8 Claims. (Cl. 123—97)

My invention relates to fuel mixture supply control means or means for controlling the supply of fuel mixture to the internal combustion engines of motor vehicles under certain critical 5 conditions.

Strictly speaking, this invention is in the nature of an improvement in devices at present on the market for the elimination of carbon monoxide gas, as well as being inherently a fuel economizer 10 or means for providing actual saving of fuel in the operation of automotive vehicles.

It is customary to control the supply of fuel mixture to the engine of a motor vehicle by means of a throttle valve operated by an accelerator 15 pedal. The closing of said valve when pressure is removed from said pedal, being limited so that a predetermined minimum supply of mixture passes to the engine, even when the latter is merely idling. This position of the throttle valve 20 is usually termed the idling position.

In general, the object of the present invention is to provide novel and useful fuel mixture control means whereby to eliminate the waste of fuel which has heretofore occurred when the 25 throttle valve was in idling position and the engine was not being used for propulsion, but remained coupled to the power transmission system of the vehicle while the latter was traveling at speed under its own momentum, say down an 30 incline, said control means also serving to shut off the excessive stream of fuel which temporarily occurs when the throttle valve is suddenly allowed to close to idling position, and thereby prevent the flushing out of the engine cylinders by 35 rich fuel mixture and the subsequent waste of lubricating oil. A further result of such a control is to eliminate back-firing through the muffler when coasting to a corner or down a hill.

Since the shutting off of gas permits the 40 momentum of the vehicle to drive the engine, instead of the engine driving the vehicle, and since under this condition the fuel supply is completely shut off, the fact that there is a saving in gas depending entirely upon the amount of coasting 45 which is done, is obvious.

Some of the devices at present on the market have been found to have various faults. For 50 example, there is one device on the market today which, in a condition such as described, shuts off the fuel supply and opens up an air supply to the intake manifold. This has been found injurious for this reason. After a heavily laden truck has gone up a long grade and goes over the crest so that it can start coasting, the effort required to climb the hill will have made the en-

gine and associated parts quite red hot. The result of now sending a stream of cold fresh air into the combustion chamber of the engine is to cause warping of the valves and other injuries to the cylinder head and housing, due to the 5 sudden changes in temperature.

An object of the present invention is to provide a device of the class described which closes off the supply of fuel whenever an automotive vehicle is coasting.

A further object of the present invention is to provide a device of the type described so constructed that it will operate automatically and conform identically to the condition of vacuum in the intake manifold.

A further object of the invention is to provide a device of the type described that is extremely simple in construction and capable of long and efficient use without becoming broken or out of order.

A further object of the present invention is to provide a device of the type described capable of attachment to standard automotive vehicle engines at present on the market.

Other objects and advantages will be more 25 apparent from the following description wherein reference is had to the accompanying four sheets of drawings, upon which

Fig. 1 is a fragmentary side elevational view of an automotive engine with the hood broken 30 away to show other parts of the engine;

Fig. 2 is a plan elevational view of my improved unit, the view being taken generally on the line 2—2 of Fig. 1;

Fig. 3 is a fragmentary side elevational view 35 of a standard form of carburetor showing generally my improved unit in position associated with the same;

Fig. 4 is a cross sectional view through my improved unit taken generally on the line 4—4 of Fig. 2 showing the same associated with the pertinent portions of the carburetor;

Fig. 5 is an enlarged sectional view through a portion of the device and associated parts taken generally on the line 5—5 of Fig. 4;

Fig. 6 is a fragmentary sectional view of a 45 modified form of device constructed for use with a dual carburetor;

Fig. 7 is a side elevational view of a modified form of the invention with parts broken in section 50 to more clearly show other parts; and

Fig. 8 is a vertical sectional view of a still further modified form of the invention.

In the embodiment of the invention which I have chosen to illustrate, I have shown in Fig. 1 55

the usual type of internal combustion automotive engine 10 constructed in the usual manner with the intake manifold 12, carburetor 14 and exhaust pipe 1. The carburetor 14 may be of one well known type having the separable housing units 16 and 18, the unit 18 being connected to the intake manifold 12 and the unit 16 being generally connected to the air filter 20 thereabove. In this and other well known forms of carburetors there is a fuel passageway 22 extending from the float chamber 24 which communicates with the interior of the carburetor 16 through the port 26 and also through passageways 28, 30, 32 and ports 34 and 36. Port 36 is what is usually known as the idling jet or the only direct supply of gasoline from the carburetor to the engine when the throttle valve 38 is completely closed, such as when the car is coasting down hill. A needle valve 40 is usually employed to regulate or control the supply of fuel through port 36 or through the idling jet.

In order to effect the functions which I have described in connection with my invention, I preferably mount a body member 42 between the separable portions 16 and 18 of the carburetor. The body portion 42 may have a flange portion 44 with an opening 46 therethrough coinciding with the conduit 48 through the carburetor. The same bolt members 50 which fasten the carburetor parts together may fasten the body 42 in position.

The body member 42 may be formed with a cylindrical boss 54 that is screw-threaded at 56 to receive a cylindrical shell member 58. I form a reduced shoulder 60 on the end of shell member 58 and fasten a diaphragm 62 in position against a peripheral seat 64 formed in the boss 54. Suitable gaskets 66 are provided on both sides of the diaphragm to provide an air-tight seal around its edge.

Diaphragm 62 may have an axially directed rod member 68 screw-threadedly connected to washer members 70 upon opposite sides of the diaphragm. In this manner movement of the diaphragm will effect movement of the rod 68. A compression spring 72 positioned against one of the washers 70 extends into the cylinder 58 against an adjusting nut 74 that is screw-threadedly mounted in the tapped end 76 of the cylinder 58. A cap member 78 formed with a reduced screw threaded portion 80 engages in the tapped opening 76 and effectively closes the end of the cylinder, a suitable sealing washer 82 being interposed between the ends. I provide an axially tapped opening 84 in the cap 82 to receive a connector 86 secured to a conduit 88. The conduit 88 may extend to and be connected by a similar connector member 90 to any desirable part of the intake manifold of the engine 10.

As previously mentioned, the diaphragm 62 is positioned within the boss 54 forming a dividing wall between a pair of chambers 92 and 94. The chamber 94 may be open to atmosphere through the vent opening 96. The chamber 92 may be in communication with conduit 88 and the intake manifold through bore 98 in the adjusting nut 74. As thus constructed it can be seen that vacuum in the manifold through conduit 88 may flex the diaphragm to enlarge chamber 94 against the action of spring 72. It is further apparent that when the vacuum is not sufficient to overcome spring 72 the spring will flex the diaphragm to the position shown in Fig. 4.

The rod 68 is in the nature of a sliding valve having a reduced diameter to provide an annular slot 100. In the normal position shown in Fig. 4, this slot will be aligned with the conduits 30 and 32 and thus permit fuel to pass downwardly to the idling jet 36. The rod 68 is slidably mounted in a suitable bore 102. An axial drill 104 through the rod 68 and connecting to the chamber 94 provides at all times atmospheric condition in the bore 102 in which the rod 68 is slidably mounted.

From the foregoing description it will be apparent that when a car is being driven over a hill or is coasting on the level and the momentum of the car is driving the motor with the carburetor valve normally closed, a supply of gasoline will be furnished through the idler jet 36. However, in view of the well known fact that with a no-load condition on the engine, such as is in effect when the vehicle is coasting, the vacuum in the intake manifold is extremely high. The unit which I have provided is so constructed that under this high vacuum the diaphragm 62 will be sucked back at the same time moving the annular slot 100 away from the passageways 30 and 32 and effectively shutting off the supply of fuel to the engine. As soon as any power at all is required from the engine with the resultant drop in the vacuum in the manifold, the spring member 72 immediately overcomes the suction and forces the sliding valve 68 forward to the position shown in Fig. 4. It will be observed that there is an adjustable stop member 110 screw-threadedly mounted in the adjusting nut 74 to prevent high suction from pulling the valve to more than a closed position of the orifice. It will be apparent that by reason of the adjusting nut 74 and the stop member 110 a mechanical adjustment of this unit can be made to suit the vacuum conditions upon any motor upon which it is desired to employ the same.

In Fig. 6 I have shown a modification of the invention suitable for use with a dual type carburetor, having two intake conduits therethrough. In this construction the body member 42 will be provided with a pair of conduits 112 capable of alignment with the conduits of the dual carburetor and it may be fastened in place in a manner to that previously described. The body member 42 may be screw-threadedly mounted in a tapped opening 114 and the valve rod 68a formed with the annular slots 100a may be mounted in a bore 116 in a separate body section 42a. It is of course understood that the slots 100a will be in alignment with the idler jet passageways 32.

In Fig. 7 I have shown a modified form of the invention in which the body member 42b may be formed with a right angle extension 42c to provide a pivot 120 for a rocker arm 122. The rocker arm 122 may be pivotally connected to a rod 124 connected to the diaphragm 62, and the opposite end of the rocker arm 122 may be pivotally connected to a comparatively short sliding valve member 68b. It will be apparent that the operation of this construction is identical with that shown in the preferred form, the only difference being in the increased leverage produced by the diaphragm to move the valve member 68b.

In Fig. 8 I have illustrated a modified form of the invention in which the body member 42c is screw-threadedly connected by a stud portion 75

42d in a tapped opening 126 in the side of the carburetor housing adjacent the idler valve 40. The rod 128 may be rigidly connected to the diaphragm and be provided with an enlarged portion 130 slidably mounted in a suitable bore 132 in the housing 42c. This bore may communicate with the passageway 32 in the carburetor. I provide a side opening 134 communicating with the bore 132. The operation of this construction is as follows: When the engine is coasting and there is a sufficiently high vacuum to draw the plunger 130 to the position shown in Fig. 8, air is admitted through the port 134 and is drawn through the passageway 32 past the idle jet 40 and into the manifold. With this construction the supply of gasoline is not entirely shut off. However, the mixture fed to the engine while the same is coasting will be greatly reduced in liquid fuel content.

20 From the above and foregoing description it will be apparent to those skilled in the art that I have provided a highly beneficial device which performs a double function in connection with the operation of the internal combustion engine 25 of an automotive vehicle. By the action of my preferred form of the invention there is absolutely no carbon monoxide gas which is emitted from the exhaust muffler when an automobile is coasting. Further, there is a distinct saving in 30 the amount of gasoline used in connection with the operation of the automobile. I have further found that when the supply of gas is shut off, that the slight amount of air which reaches the combustion chamber above the pistons during a 35 coasting operation, serves to burn the carbon on the cylinder walls and in the cylinder head. This is due to the fact that as only air is being drawn in and in a very slight amount, the continued ignition in the cylinders causes the carbon 40 to burn in the presence of the oxygen in the air.

While I have illustrated and described a specific embodiment of my invention and several modifications thereof which are advisable under certain conditions, I contemplate that changes 45 and modifications may be made in the specific details shown, and I do not wish to be limited in any particular. Rather what I desire to secure and protect by Letters Patent of the United States is:

50 1. A device of the character described comprising a shut-off member adapted to be mounted in the passageway to the idling jet of a carburetor, a cylinder forming part of said member, said shut-off member having a portion mounted 55 in said cylinder, a conduit adapted to extend from said cylinder to the intake manifold of an internal combustion engine whereby the actuation of said shut-off member is adapted to be directly responsive to the vacuum condition in 60 the manifold, resilient means urging the shut-off member to open position, and adjustment means associated with said resilient means for adjusting the tension of the resilient means whereby 65 to control the operation of the shut-off member in accordance with a predetermined vacuum condition in the manifold.

2. A device of the character described comprising a shut-off member adapted to be mounted 70 in the passageway to the idling jet of a carburetor, a cylinder forming a part of said member, said member having a diaphragm portion mounted in said cylinder, a conduit adapted to extend from said cylinder to the intake manifold of an internal combustion engine whereby the 75 actuation of said shut-off member is adapted to

be responsive to the vacuum condition in the manifold as directed against said diaphragm portion, resilient means urging the shut-off member to open position, and adjustment means associated with said resilient means for adjusting the tension of the resilient means whereby to control the operation of the shut-off member in accordance with a predetermined vacuum condition in the manifold.

3. A device of the character described comprising a slide valve adapted to be mounted in the passageway to the idling jet of a carburetor, a cylinder forming a part of said valve, said valve having a diaphragm attached thereto and mounted in a chamber in said cylinder, a conduit 15 adapted to extend from said chamber to the intake manifold of an internal combustion engine whereby the actuation of said slide valve is adapted to be directly responsive to the vacuum condition in the manifold, resilient means urging the 20 valve to open position, and adjustment means associated with said resilient means for adjusting the tension of the resilient means whereby to control the operation of the valve in accordance with a predetermined vacuum condition in the mani- 25

30 4. A unitary device adapted to be positioned in the fuel mixture intake of an internal combustion engine between two portions of the carburetor, said unit having upper and lower flat surfaces for attachment to said housing units, a fuel conduit in said unit extending between the two surfaces, a relatively small passageway in said unit parallel to said first named conduit and separate therefrom, said passageway terminating at 35 both of said faces in aligned apertures, a slidably mounted valve member in said unit for opening and closing said passageway, and vacuum responsive means independent of the vacuum in said conduit and passageway for actuating said valve to closed position, said opposed flat surfaces 40 being parallel and said conduit and passageway extending normally thereto in parallelism for providing the continuation of carburetor passageways.

45 5. A unitary device adapted to be positioned in the fuel mixture intake of an internal combustion engine between two portions of the carburetor, said unit having upper and lower flat surfaces for attachment to said housing units, a fuel conduit in said unit extending between the two surfaces, a relatively small passageway in said unit parallel to said first named conduit and separate therefrom, said passageway terminating at both of said faces in aligned apertures, a slidably mounted valve member in said unit for opening and closing said passageway, vacuum responsive means independent of the vacuum in said conduit and passageway for actuating said valve to closed position, said opposed flat surfaces being parallel 55 and said conduit and passageway extending normally thereto in parallelism for providing the continuation of carburetor passageways, said vacuum responsive means comprising a diaphragm operatively connected with said valve member, a closed chamber adjacent said diaphragm, a passage communicating with said chamber and adapted to be placed in communication with the intake manifold suction, and resilient means normally urging the valve to open 60 position.

6. A unitary device adapted to be positioned in the fuel mixture intake of an internal combustion engine between two portions of the carburetor, said unit having upper and lower flat surfaces for attachment to said housing units, a fuel 70

conduit in said unit extending between the two surfaces, a relatively small passageway in said unit parallel to said first named conduit and separate therefrom, said passageway terminating at 5 both of said faces in aligned apertures, a slidably mounted valve member in said unit for opening and closing said passageway, vacuum responsive means independent of the vacuum in said conduit and passageway for actuating said valve to closed 10 position, said opposed flat surfaces being parallel and said conduit and passageway extending normally thereto in parallelism for providing the continuation of carburetor passageways, said valve means comprising a blind bore in said unit, 15 a member slidable longitudinally in said blind bore, and a passageway in said member communicating with the inner extremity thereof and with atmosphere.

7. A unitary device adapted to be mounted 20 upon the carburetor of an internal combustion engine and comprising a member having a surface configurated for connection to a portion of said carburetor, a passageway opening adjacent said surface and extending inwardly into said 25 unit, a valve in said passageway, a vacuum chamber independent of said passageway, suction re-

sponsive means in said vacuum chamber, said suction responsive means being operatively connected to said valve for operation thereof, and conduit means communicating with said vacuum chamber and adapted for connection to intake 5 manifold suction.

8. A unitary device adapted to be mounted upon the carburetor of an internal combustion engine and comprising a member having a surface configurated for connection to a portion of 10 said carburetor, a passageway opening adjacent said surface and extending inwardly into said unit, a valve in said passageway, a vacuum chamber independent of said passageway, suction responsive means in said vacuum chamber, said 15 suction responsive means being operatively connected to said valve for operation thereof, and conduit means communicating with said vacuum chamber and adapted for connection to intake manifold suction, said connection surface comprising a helically threaded portion formed about 20 said opening and adapted for insertion in a complementary opening in a carburetor communicating with the jet passageway thereof.

ADDISON C. HOOF. 25
